METHOD AND APPARATUS FOR DRILLING OIL WELLS

Application filed May 2, 1931. Serial No. 534,481.

- This invention relates in a general way to the art of drilling wells, and is more particularly related to a drilling method and apparatus whereby the drilling cost per well is 5 greatly reduced. It is well known to those familiar with the art that the cost of building an ordinary derrick with foundations such as used in modern drilling operations is a major factor in the complete cost of drilling a well. 10 It is also well known that in certain fields to obtain a maximum production from the oil zone it is necessary that the wells be situated close together, making it necessary to construct a great number of derricks for the purpose of draining a comparatively small territory. In some regions there are several oil producing zones or horizons situated one above the other so that a well may be drilled to one zone and before the next lower zone 15 can be reached this first zone must either be drained of its oil or another well must be drilled immediately adjacent the first well. The former procedure may prevent an operating company reaching the second zone before another company has drained the second zone of its oil, or if a secondary structure is constructed it materially increases the cost of the oil obtained from the second zone above what its cost would have been had the same 20 derrick structure been used to reach the underlying zone or zones. 25 In some locations, the most productive oil zones have been found to be located below the ocean at an appreciable distance from the shore. In these territories it has become a practice to build piers out to and above the oil zone upon which the derrick structures are located. The construction of these piers and the necessary underwater construction at 30 tending the building of the derrick structure entails considerable expense, making the cost of the foundation and pier alone in the neighborhood of from \$50,000.00 to \$100,000.00 per location. 35 In other locations due to rough and rocky terrain the initial location and foundation costs in advance of actual drilling represent a large proportion of the total well costs. 40 It is the primary object of this invention to produce a well drilling method whereby a single derrick structure may be used in the drilling of two or more wells. This object may be accomplished when the derrick structure is situated on the ground by merely shifting the rotary table on the derrick floor so that the wells may be spudded in or started in close relation with each other, and if the wells are to terminate in the same zone it is preferable that some form of bit guide be employed to direct the bore holes into angularly disposed relation with each other so that the different wells terminate in the oil zone at considerable distances from each other. We consider it preferable, both in cases where the derrick structure is situated on the surface of the ground and where the derrick structure is situated above a body of water, to employ a conductor pipe which is of comparatively large diameter and which may be provided with dividing means or partitions to form a plurality of compartments through which the drill stem may be operated in drilling the different wells. This conductor pipe may be placed immediately upon the floor of the ocean in the case of an underwater well, or it may, in either an underwater well or a well started from the surface of the ground, be placed in a large diameter bore hole which is drilled to a comparatively shallow depth below the surface of the ground or the derrick. These bore holes may be from several feet to several hundred feet in depth and, as pointed out above, if the different wells are to terminate in the same zone, it is preferable that some form of bit guide be situated at or near the bottom of the bore hole for directing the auxiliary bore holes into angular relation with each other. Where the wells are to terminate in different zones, however, the deflecting guide may not necessarily be employed, under which circumstances the different wells may terminate at a point situated vertically below the derrick. Under any circumstances it is important in the practice of the method contemplated by this invention that the operation of the drill be carefully regulated through the use of varying drilling weights, methods, and apparatus (such as whipstocks), so that the second and subsequent wells 55 60 65 70 75 80 85 90 95 100

bore holes drilled from the same foundation do not interfere with prior drilled holes. Various precautionary measures have been developed in this particular art for regulating the operation of the drill bit, such as the frequent use of surveying equipment and the regulation of the weight on the bit. This procedure is so well known that it need not be further discussed here.

10 It is a further object of this invention to produce a novel type of casing or conductor tubing especially adapted for use in connection with this invention. It is a noteworthy feature of this casing or conductor tubing 15 that it is provided with a divider or partitioning member which may be removably or fixedly mounted therein and the divider or partitioning member may be associated with a bit guide provided with bit deflecting surfaces which are arranged so as to cooperate with the compartments formed by the divider to direct the movement of the bit so that the bore holes produced thereby are arranged in angularly disposed relation with 20 each other.

25 The details in the method and apparatus contemplated by this invention, together with other objects attending its production, will be best understood from the following 30 description of the accompanying drawings which are chosen for illustrative purposes only, and in which—

35 Fig. 1 is a sectional elevation showing the lower portion of a derrick structure used in producing underwater wells and illustrating the manner in which wells of the type contemplated by this invention are produced;

40 Fig. 2 is a plan section which may be considered as having been taken in a plane represented by the line 2—2 in Fig. 1;

Fig. 3 is a perspective view showing one form of bit guide which may be used in the method contemplated by this invention;

45 Fig. 4 is a small sectional elevation which is more or less diagrammatic and illustrates another manner of carrying out the invention;

50 Fig. 5 is a view similar to Fig. 4 illustrating still another manner of practicing the process contemplated by this invention; and

55 Fig. 6 is a perspective view showing a modified form of bit guide.

More particularly describing the invention as herein illustrated, reference numeral 11 indicates a derrick foundation which is shown as comprising a base portion 12 which is built upon the shale 13 of the floor or bed of the ocean or other body of water and a hollow derrick supporting column 14 which 60 rests upon the base portion 12 and supports the derrick floor 15. Reference numeral 16 indicates the lower portion of the derrick structure and reference numeral 17 indicates a pier by means of which the derrick structure 65 may be reached from the mainland. The

70 hollow column 14 is made so that its interior is sufficiently large to permit workmen to enter therein and in view of the fact that the base member 12 is situated on the floor of the ocean, it will be observed that this column 75 is water tight and must be made of sufficient strength to withstand the hydrostatic pressure and movement of the water surrounding it.

75 The derrick floor 15 carries a rotary table 20 of the usual type which is utilized for the operation of a drill string for advancing the various bore holes beneath the derrick structure. In carrying out the process contemplated by this invention in connection with apparatus of the type shown in Fig. 1, the procedure followed is to first drill a large diameter bore hole as indicated by reference numeral 21. This bore hole may be from 30 to 50 inches in diameter and although it is hereinafter referred to as being of comparatively shallow depth, it will be understood that it may extend from several feet to several hundred feet beneath the surface at 80 which it enters the formation. After the bore hole 21 has been advanced to the desired depth, a conductor tubing 22 is placed therein. The conductor tubing 22 may extend clear to the bottom of the bore hole 21, it may be driven a slight distance below the bottom 85 21, or it may terminate above the bottom of the bore hole 21 without departing from the scope of this invention.

85 As was pointed out in the fore part of the specification, in the event the various wells 90 are to terminate in the same oil zone, it is preferable that these wells be drilled so that they bear an angular relation with each other and consequently terminate in any one oil zone at appreciable distances one from the other. For the purpose of directing the course of the auxiliary bit or bits for producing the smaller diameter auxiliary bore holes, we propose to use a bit deflecting member at or near the lower end of the conductor tubing 22. This guide member is provided with a plurality of bit deflecting surfaces corresponding to the number of auxiliary bore holes which are to be produced and such surfaces are inclined outwardly at the desired 100 angle for properly directing the course of the auxiliary bore holes. Reference numeral 23 indicates one form of bit guide which may be used in the process contemplated by this 105 invention.

110 For the purpose of directing the movement of the bit so that it is finally brought into engagement with the proper deflecting surface, we find it desirable to use within the conductor pipe a divider or partitioning member which is generally indicated by reference 115 numeral 24 and is shown as being secured at its lower end to the top surface of the bit guide 23. This divider or directing member 24 is shown as comprising a plurality of 120 125 130

plates or panels which may extend a short distance up from the bottom of the hole or may extend throughout the entire length of the conductor tubing 22, as shown. The dividers may be loosely or rigidly mounted in the bore hole or conductor tubing and may or may not be secured to the upper end of the bit guide. The partitioning member or divider may, therefore, be installed prior to, during or subsequent to the installation of the conductor pipe, or it might even be used independently of the conductor pipe. The number of these panels is such as to divide the conductor pipe into a plurality of longitudinal compartments which correspond in number to the number of bit deflecting surfaces on the guide member 23.

Referring to Fig. 3 it will be noted that the bit guide is provided with outwardly sloping depressions 30, 30a and 30b which provide three bit deflecting surfaces in this member. The divider or partitioning member 24 is shown as comprising panels 31, 31a and 31b which are secured by means such as welding, to the upper end portion of the block 23 and are situated between the depressions 30, 30a and 30b. In order that a bit advanced downwardly through any one of the compartments formed by the panels will be directed into the corresponding depression and into engagement with the bit deflecting surface therein, we provide the upper surface of the block 23 with rounded shoulders, as indicated by reference numeral 32, thus eliminating any square shoulders or right angle surfaces upon which the bit might be hung up.

In Fig. 1, reference numeral 35 indicates an auxiliary bore hole which has been drilled by means of a bit passing through the compartment 36a of the conductor pipe 22. This bore hole is shown as having been complete and as containing a casing 37 which terminates at the upper end of the conductor pipe 22 where it is equipped with the usual type of fittings 38, through which the oil is delivered from the well in a pipe indicated by reference numeral 39.

Reference numeral 40 indicates a drill bit which is shown as being in engagement with a deflecting surface 30 of the bit guide 23. This drill bit is attached to the lower end of a drill string 41 which passes downwardly through the compartment 36 in the conductor tubing 24 and is provided at its upper end with a kelley 42 whereby it is rotated through the medium of the rotary table 20.

It will be understood that in the carrying out of the process contemplated by this invention, the rotary table is positioned with its axis directly above the central portion of the main large diameter bore hole 21 during the drilling of this bore hole. When the auxiliary bore hole such as bore hole 37 and the one which is being produced by the bit 40, are being drilled, it is advisable to shift the

rotary table so that its axis is in line with the central portion of the compartment in the conductor tubing through which the auxiliary bore hole is to be drilled. The shifting of the rotary table may be carried out in any well known manner and means for effecting such a shifting movement are no part of this invention and are consequently not discussed here.

In Fig. 4 we illustrate the manner in which two or more bore holes might be drilled in angular relation with each other directly from the surface of the ground below the derrick structure 16a. These bore holes are indicated by reference numerals 50 and 50' and are preferably started by placing a guide member at the surface of the ground which may be pointed at its lower end and driven into the ground, as indicated by reference numeral 51.

In Fig. 5 we illustrate the manner in which the invention may be carried out in drilling two or more bore holes to different levels to obtain oil from two or more different oil producing zones below the same derrick structure 16b. These bore holes are indicated by reference numerals 52 and 52' and are shown as being substantially parallel. When this procedure is followed it may not be necessary to use a bit deflecting or directing member at the ground surface, but as pointed out above, it is important that the drilling operations be carefully controlled so that there is no tendency for the course of any bore hole to interfere with others drilled from the same derrick.

Fig. 6 illustrates a modified form of bit directing and bit guiding member which is shown as comprising panels 24' between which deflecting blocks 23' are mounted.

It is to be understood that while we have herein described and illustrated one preferred procedure and certain preferred forms of apparatus followed and used in practicing this invention, the invention is not limited to the precise operation and apparatus described above, but includes within its scope whatever changes fairly come within the spirit of the appended claims.

We claim as our invention:

1. A well drilling method which comprises: drilling a comparatively shallow large diameter bore hole; placing a partitioned conductor pipe in said bore hole; and drilling a plurality of small diameter bore holes in the compartments formed by the partition in said conductor pipe.

2. A well drilling method which comprises: drilling a comparatively shallow large diameter bore hole; placing a directing member having a plurality of bit deflecting surfaces in the bottom of said bore hole; and advancing a small diameter bit into said large diameter bore hole successively past different deflecting surfaces on said directing member.

to form a plurality of angularly disposed small diameter bore holes at the bottom of said large diameter bore hole.

3. A well drilling method which comprises: 5 drilling a comparatively shallow large diameter bore hole; placing a directing member having a plurality of bit deflecting surfaces and a partitioned conductor pipe having a plurality of compartments in alignment with 10 the deflecting surfaces on said directing member in said bore hole; and successively drilling a plurality of small diameter bore holes from said large diameter bore hole by advancing drill bits through said compartments 15 and past the deflecting surfaces on said directing member.

4. A method of drilling a well below a body of water which comprises: building a foundation on the bed of said body of water; 20 mounting a drilling derrick structure on said foundation; drilling a large diameter bore hole through said foundation; placing a conductor pipe in said large diameter bore hole; and drilling a plurality of small diameter 25 bore holes from said large diameter bore hole at the bottom of said conductor casing.

5. For use in drilling oil wells: a conductor casing; a divider in said conductor casing separating the conductor casing into 30 a plurality of longitudinal passages; and a directing member at the lower end of said conductor tubing having a bit deflecting surface positioned substantially in alignment with each of said longitudinal passages.

35 6. For use in drilling oil wells: a bit guide having a plurality of angularly disposed bit deflecting surfaces formed thereon.

7. A bit guide of the class described embodying: a block formed with a plurality of 40 bit deflecting surfaces thereon.

8. A bit guide of the class described embodying: a block provided with a plurality of angularly disposed sloping depressions to form bit deflecting surfaces which diverge 45 outwardly toward the bottom of the block; and divider plates secured to the upper end of said block between said depressions.

9. For use in drilling oil wells: a conductor casing; and a bit guide at the lower 50 end of said casing, said guide being provided with a plurality of angularly disposed bit deflecting surfaces.

10. A well drilling method which comprises: drilling a comparatively shallow 55 large diameter bore hole; partitioning said hole to form a plurality of longitudinal chambers; and drilling a small diameter bore hole through each of said chambers.

11. A method of drilling wells below a 60 body of water which comprises: building a foundation on the bed of said body of water; mounting a drilling derrick structure on said foundation; and drilling a plurality of bore holes directly below said foundation.

65 12. A method of drilling wells below a

body of water which comprises: building a foundation on the bed of said body of water; mounting a drilling derrick structure on said foundation; and drilling a plurality of angularly disposed bore holes below said foundation. 70

13. A well drilling method which comprises the steps of: building a single derrick structure; utilizing said derrick structure to drill a plurality of wells therebelow; and extending an oil delivery tube from said derrick structure into each of said wells. 75

In testimony whereof, we have hereunto set our hands at Los Angeles, California, this 25th day of April, 1931.
